UNITED STATES PATENT OFFICE

SYLVESTER A. JOHNSON, OF NORTH PROVIDENCE, RHODE ISLAND, ASSIGNOR TO SPEIDEL BROS., OF PROVIDENCE, RHODE ISLAND, A FIRM COMPOSED OF ALBERT E. R. SPEIDEL AND EDWIN F. M. SPEIDEL

EXTENSION DEVICE

Application filed May 9, 1930. Serial No. 451,009.

This invention relates to a foldable extension device, and has for its object to provide means for causing the sections to fold in a predetermined definite relation one upon the other.

A still further object of the invention is to provide a series of foldable sections one of which will partially nest in two other sections to reduce the thickness of the device.

10 A still further object of the invention is to provide open frame sections hinged together by a section of a dimension to swing thereto, and to form stops to control the swinging of the sections, causing them to fold only 15 by a swinging in a predetermined direction whereby the parts will always be brought in the same relation.

With these and other objects and advantageous features in view, the invention consists of a novel arrangement of parts more fully disclosed in the detailed description following, in conjunction with the accompanying drawings, and more particularly set forth in the appended claims.

25 In the drawings:

Fig. 1 is a top plan view of the extension device in folded position and connected in a bracelet of which it forms a part;

Fig. 2 is a top plan view of the sections in 30 extended position;

Fig. 3 is a bottom view thereof with the side walls of one of the channel sections in section;

Fig. 4 is a central sectional view of the 35 device in extended position;

Fig. 5 is a bottom view, partly in section, of the device in partly folded position;

Fig. 6 is a central sectional view of the device in folded position.

40 It is desirable to form extension devices as thin and compact as possible consistent with strength and functional utility, which I have accomplished by providing frame sections having open centers which will receive another section either wholly or partially therein to reduce the thickness of the device when in folded position, and as such sections when hinged together may swing toward either side of a section to which it is connected, I have provided stops at the hinged connec-

tions to prevent the swinging movement of the sections in one direction but permit relative swinging movement toward the other side of the section, whereby when the sections are unfolded and movement is exerted on what may be termed a dead center, the section must swing in one direction only to a certain definite predetermined relation in order to move to folded position; and the following is a detailed description of the present embodiment of this invention illustrating the preferred means by which these advantageous results may be accomplished.

With reference to the drawings, 10 designates a channel shape top section having side walls 11 to which is pivotally connected the open frame section 12 having trunnions 13 pivotally mounted in the side walls 11 and an opening 14 to receive the intermediate section 15 which hingedly joins the section 12 and the open frame section 16 by having its end portions 17 rolled about the end bars 18 and 19 of the same to form a hinge joint. The section 16 has an opening 20 and is also provided with trunnions 21 pivotally mounted in the side walls 22 of the bottom section 23 of the device.

When in folded position, the intermediate section 15 is of an outer lateral dimension slightly less than the lateral dimension across the openings 14 and 20 so that when in folded position, the intermediate section 15 lies partially within the opening 14 and partially within the opening 20, as illustrated in Figure 6, so that sections 12 and 16 are in substantially contiguous relation throughout their length, and thus the thickness of the device may be reduced by at least the thickness of the section 15 to form a more compact construction.

In order to prevent the section 15 from swinging toward either side of the sections 12 and 16, I have provided stops by forming projections 24 on the section 12 to extend along one side of the section 15 when in extended position, and stops formed by projections 25 on the section 16 to engage the end of the cross bar of the section 15, both of which prevent folding of the sections 12 and 16 toward one side of the section 15, but per-

- mit a folding movement toward the other side thereof and thus the sections must fold in a definite predetermined relation which will bring the channel sections 10 and 23 into the desired relation to permit inter-engagement of the side walls 11 and 22 for clasped relation. The walls 22 are not of sufficient depth to engage the section 12 in its folded position in the section 10.
10. The end sections 10 and 22 are provided with hooks 26, 27 to engage the end of one of the links 28 of the bracelet for joining the extension device in connected relation therewith.
15. From the above it will be apparent that I have provided a construction in which the parts are nested to reduce thickness and one in which the parts must fold in definite desired relation to facilitate the closing of the 20 device when on the arm by reason of its being made to close in the proper position only and not permitted to fold incorrectly which would cause a repeat of the operations to correct the error.
25. While I have described certain construction forms which embody the principles of my invention, it is obvious that other desired changes in arrangement may be made within the spirit and the scope of the invention as 30 defined in the appended claims.
- I claim:
1. In an extension device, a pair of sections, means for hingedly securing said sections together, said hinge means being located at the ends of the sections and so formed and arranged as to permit folding of the sections one on the other along either surface of the different sections, and stop means at the hinge connection between said 35 sections and carried by one of said sections to permit opening of said sections to an end-to-end substantially aligned extended position but permit swinging from extended position to folded position in but one direction.
  40. 2. In an extension device, a pair of similar open frame sections, an intermediate section hinged at its ends to said frame sections, the relative proportion of said openings and intermediate section permitting the intermediate section to be partially received in each of said frame sections, whereby said open frame sections may lie in substantially contiguous relation throughout their length when in folded position.
  45. 3. In an extension device, a pair of open frame sections providing side and end bars, a section hinged to said frame sections and having an outer dimension substantially that of the dimension of the openings in the frame 50 sections to receive it therein, whereby said open frame sections may lie in substantially contiguous relation throughout their length when in folded position.
  55. 4. In an extension device, a pair of similar open frame sections, an intermediate section 55
- hinged at its ends to said frame sections, the relative proportion of said openings and intermediate section permitting the intermediate section to be partially received in each of said frame sections, whereby said frame sections may lie in substantially contiguous relation throughout their length when in folded position, and stops at the hinge connections between said sections preventing swinging of said sections one about the other in one direction, whereby folding will occur in the desired direction to bring the parts into desired relation. 70
5. In an extension device, a pair of open frame sections providing side and end bars, a section hinged to said frame sections and having an outer dimension substantially that of the dimension of the openings in the frame sections to receive it therein, whereby said open frame sections may lie in substantially contiguous relation throughout their length when in folded position, and stops at the hinge connections between said sections carried by one section to engage the other, preventing swinging of said sections one about the other in one direction, but permitting swinging in the other direction, whereby folding will occur in the desired direction to bring the parts into desired relation. 75
6. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 80
7. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 85
8. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 90
9. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 95
10. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 100
11. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 105
12. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 110
13. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 115
14. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 120
15. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 125
16. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position. 130

ranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position, said stop means consisting of projections on one of the sections at the hinge joint to engage the other section to which it is connected.

9. In an extension device, a pair of end sections, an intermediate section, hinges connecting said intermediate section to said end sections, said hinges being so formed and arranged as to permit the intermediate section at its ends to swing towards either side of each end section, stop means at each of the hinge connections permitting said sections to lie in an end to end extended position, said stop means preventing swinging movement of the end sections towards one side of the intermediate section, but permitting swinging movement towards the other side thereof in movement from open to closed position, said stop means consisting of projections on one end section at the hinge joint to engage the intermediate section to which it is connected.

In testimony whereof I affix my signature.
SYLVESTER A. JOHNSON.
